BUTTON OR SIMILAR ARTICLE

Louis A. Petitclair, Granite City, Ill.

Application December 30, 1954, Serial No. 33,760

Term of patent 3½ years

(Cl. D17—2)

Fig. 1

Fig. 2

Fig. 3

Fig. 4

Fig. 5.

Fig. 6

Fig. 1 is a frontal elevational view of the button or similar article in a closed position showing my new design.

Fig. 2 is a frontal elevational view of the button or similar article in an open position.

Fig. 3 is a top plan view.

Fig. 4 is an end view looking toward either end of Fig. 1.

Fig. 5 is a perspective view of the button or similar article in an open position showing the inner raised annular ridge.

Fig. 6 is a perspective view of the button or similar article in an open position showing an annular depression for the reception of the raised annular ridge.

I claim:

The ornamental design for a button or similar article, as shown and described.
